UNITED STATES PATENT OFFICE.

MARIE DE PALKOWSKA AND ALFRED BULLARD, OF NEW YORK, N. Y.

EXERCISING MACHINE.

1,158,003.

Specification of Letters Patent. Patented Oct. 26, 1915.

Application filed July 2, 1915. Serial No. 37,740.

To all whom it may concern:

Be it known that we, MARIE DE PALKOWSKA, a citizen of the United States, and ALFRED BULLARD, a subject of the King of Great Britain, residing at New York, in the borough of Manhattan and State of New York, have invented or discovered certain new and useful Improvements in Exercising Machines, of which improvements the following is a specification.

Our invention relates to exercising machines, and, more particularly, it is a machine of that sort which in its use involves the same bodily motions and the exercising 15 of the same muscles as the operation of sawing wood with a bucksaw on a sawhorse.

The invention is illustrated in the accompanying drawings of which—

Figure 1 shows the exercising machine of 20 our invention in perspective. In this view, one of the foot rests with which the machine is equipped is shown in folded position, while the other is shown in extended position, and one of the saw handles is 25 shown detached. Fig. 2 is a view in side elevation of the sawhorse with the attached foot rests knocked down or collapsed, in the condition in which it will be shipped or laid aside when not in use. Fig. 3 is a view in 30 perspective of the dummy saw log which is part of the machine, the several major parts of the saw log being shown in this figure separated one from another for purposes of illustration. Fig. 4 is a vertical longitudinal section through the dummy saw log. Fig. 5 is a view in plan of a portion of the 35 dummy saw log, the portion at the left, Fig. 3, (part marked G in Fig. 3 being removed). Fig. 6 is a view in perspective of the tray 40 for containing the miniature facsimiles of lengths of cord wood which constitute the tally or registering counters of the machine. Fig. 7 shows one of these miniature lengths of cord wood in perspective.

Referring first to Fig. 1, the machine will 45 be seen to consist of a dummy sawhorse whose cross arms 1 and 2 are pivoted one to another, of a dummy sawlog clamped between the upper ends of the arms 1 and 2, of 50 a dummy saw C movable in a transverse slot in the dummy saw log F, and of foot rests A and B.

It will be observed that the foot rests A and B are secured to the lower ends of the 55 arms 1 and 2 of the dummy sawhorse so that when extended, and when the machine is in

use, the users standing on these foot rests will more securely anchor the machine. The foot rests are collapsible and, as is particularly shown in Figs. 1 and 2, the sawhorse 60 may be knocked down and the foot rests collapsed as a matter of convenience in shipping and storing. When the dummy sawhorse is expanded, and the dummy saw log F is clamped between the upper ends of the 65 crossed arms (which arms will be provided with proper seats in which the dummy saw log may rest), the whole may be secured in any desired way, as by means of a tension member E connecting the lower ends of the 70 arms 1 and 2, which connecting member may be tightened and loosened by a thumbscrew D.

Referring particularly to the dummy saw log, as it is particularly illustrated in Figs. 75 3 and 4, it will be seen to be formed preferably of an octagon shape for ready securing in the dummy sawhorse. It is provided with a transverse slot in which the dummy hand-saw is received, and in which the 80 dummy hand-saw moves. As is best shown in Fig. 5, this dummy saw log is divided on an approximately horizontal medial plane, and the upper portion of the log is again 85 divided transversely to form the slot. The 90 opposite walls of this slot are conveniently formed of two blocks or plates I and J of suitable material, as for example brake-lining or indurated fiber, which is durable and will not be injuriously heated by friction. 95 The spacing of these two plates I and J from one another and therefor the effective width of the slot and the closeness of engagement of the two plates upon the opposite faces of the dummy saw introduced between them 100 may be accomplished by having one of the two, for example the plate J (Fig. 4), movable to and from the plate I. Fig. 4 shows plate J supported in a suitable space within the dummy saw log by means of the slotted 105 brackets 3. The slotted brackets allow the plate J to move toward and away from its fellow plate I. The plate J is borne on a stem N, through an intervening compression spring connection L, and the stem N is slotted and hung in the space within the log, 110 in the manner indicated at M. A screw extends through and though rotatable is longitudinally immovable in the end of the log. It is provided externally with a handle K. This screw at its inner end engages the stem N. Thus, by the turning of the handle K

the position of plate J may be adjusted, the width of the slot controlled; the closeness of fit of the saw, the frictional resistance to the drawing of the saw to and fro in the slot, 5 and the amount of muscular effort involved in using the machine, may be varied and adjusted as desired. The presence of the spring L (which ordinarily will be a spring of considerable resistance) allows plate J to 10 adjust itself to inequalities in the thickness of the blade of the dummy saw, and affords a steadier resistance to the operation of the machine.

A block O is arranged in a suitable guide-way in the body of the dummy saw log (see 15 Fig. 3) and is movable in the direction of the length of the slot already described. Furthermore, the block O is itself provided with a slot which, when the parts are assembled, registers with and forms a continuation of the slot formed by the plates I, J. When the parts are assembled, and the saw C is in place, and when the saw is moved to 20 and fro in the slot, the engagement of the blade of the saw with the block O will cause it to move longitudinally in its runway, first in one direction and then in the other. The ends of the runway of the block O are 25 preferably provided with elastic bumpers P. The amount of traverse of block O is evidently far less than the extent of the stroke of the saw, but the frictional engagement of the saw with the block will carry it from one 30 end of the runway to the other, and when it abuts upon the end of its runway, the saw in its further traverse will slide in the slot in the block O. And it will be seen that, 35 as the saw is drawn to and fro in the dummy saw log after the manner in which a hand-saw is operated in sawing a log of wood, the block O will reciprocate to and fro in its runway, oscillating in accordance with the reciprocating movement of the saw blade.

A tally device is provided, and the tally 40 device operates in response to the shifting of the block O, and thus a record is automatically kept of the number of strokes of the saw, and the users of the machine have a check upon the amount of effort they are 45 expending. As shown in the drawings, a tray (Fig. 6) adapted to receive and sustain a number of miniature dummy sections of cord wood (Fig. 7) may be introduced within the dummy saw log in the manner indicated in Figs. 4 and 5. An orifice W is 50 formed through the lower part of the dummy log and through this orifice the dummy sections of cord wood escape. A suitably controlled escapement apparatus is arranged 55 between the otherwise open lower end of the tray and the orifice W and this mechanism, whose action is controlled by the shifting of the block O, determines the rate of the feed 60 and escape of the small dummy sections of cord wood. This escapement consists of a

drum, in this case formed in two parts, V V, in the circumference of which drum is formed a recess of suitable size to receive these dummy lengths of cord wood, one section at a time. With each revolution of the 70 drum, one section is carried from the lower end of the tray to the escape orifice W. The drum V V is rotated by means of a ratchet T mounted rigidly on the axle of the drum, and a pawl S is provided for turning the 75 ratchet T. Each reciprocation of the block O in its runway causes the pawl S to make its double stroke first forward and then back, operative connection being had through a bell-crank lever Q pivoted at R. A spring- 80 impelled pawl U prevents the retraction of the ratchet T on the backward stroke of the pawl S.

As particularly shown in Fig. 6, the edges of the tray Y may overhang, to provide for 85 the feeding forward of the succession of dummy sections of cord wood in an orderly manner. A lock Z may be provided, serving, when in the full line position of Fig. 6, to hold the dummy sections of cord wood in 90 place in the tray and, when turned by means of the connecting rod X to the dotted line position (Fig. 6) leaving the contained sections of cord wood free to escape to the drum V V, and at the same time by engaging block 95 a a securing the tray in place. As particularly shown in Fig. 4, the tray when in place is inclined, to afford the proper feed of the dummy sections of cord wood to the escapement drum V V.

For every double stroke of the dummy saw the ratchet T will advance one tooth; if the ratchet be provided with forty-eight teeth, ninety-six single strokes of the saw will be required to release a single one of the miniature logs of the registering mechanism. Assuming that the amount of effort expended in drawing the saw ninety-six times back and forth in the slot in the dummy saw log is sufficient to saw through a six-inch 110 log, the release of thirty-two logs will indicate the amount of work required to saw a quarter of a cord of wood. If then the tray Y be made of suitable size and initially charged with thirty-two miniature pieces of 115 cord wood, the users of the machine may, in effect, cut a quarter of a cord of wood or any desired fraction thereof.

We claim as our invention:

1. In an exercising machine, a knock-down 120 dummy sawhorse whose crossed arms are pivoted one to another, a dummy saw log provided with a transverse saw-receiving slot clamped between the upper ends of the arms of said horse, a dummy saw introduced 125 in and capable of being drawn to and fro in said slot, and means for securing said arms when the said saw log is clamped between them.

2. In an exercising machine, a knock-down 130

dummy sawhorse whose crossed arms are pivoted one to another, seats for a dummy saw log formed in the upper ends of the arms of said horse, and collapsible foot-rests 5 secured to the lower ends of the arms of said horse, a dummy saw log provided with a saw-receiving slot capable of being seated between the arms of said sawhorse, and a dummy saw capable of being drawn to and 10 fro in said slot.

3. In an exercising machine the combination of a pair of friction plates, a blade introduced between said plates and capable of being drawn to and fro while engaged by 15 said plates, and means for adjusting the said plates in the closeness of their engagement with said blade.

4. In an exercising machine the combination of an elongate body, a transverse slot in 20 said body, a block movable within said body to and fro in the direction of the length of said slot, said block being provided with a slot which registers with the slot in the containing body and forms part thereof, a blade 25 movable to and fro in the said slot formed in part in said elongate body and in part in said block as aforesaid, a tally device, and means for operating said tally device in coordination with the to and fro movement of 30 said block.

5. In an exercising machine, the combination of a dummy saw log provided with a transverse slot, a dummy saw movable to and fro in said slot, a space within said dummy log provided with an orifice, a feed 35 device controlling the escape through said orifice of a quantity of dummy miniature log sections contained in the space within the said dummy log, and means for operating said feed device in coördination with the to 40 and fro movement of said dummy saw in its slot.

6. In an exercising machine the combination of a dummy saw log provided with an internal recess, a tray movable to and from 45 position within said recess, an orifice opening from said recess, an escapement device arranged between said tray when in position in said recess and said orifice, a dummy saw movable in a slot in said dummy saw log, 50 and means for operating said escapement device in coördination with the movement of said dummy saw in its slot.

In testimony whereof we have hereunto set our hands.

MARIE DE PALKOWSKA.
ALFRED BULLARD.
